UNITED STATES PATENT OFFICE

HARRY C. PRICE, OF YOUNGSTOWN, OHIO, ASSIGNOR TO THE UNION SWITCH & SIGNAL COMPANY, OF SWISSVALE, PENNSYLVANIA, A CORPORATION OF PENNSYLVANIA

HIGHWAY-CROSSING PROTECTION

Application filed April 24, 1928. Serial No. 272,375.

My invention relates to highway crossing protection, that is, to apparatus for protecting the intersections of railways and highways.

5 I will describe two forms of apparatus embodying my invention, and will then point out the novel features thereof in claims.

In the accompanying drawing, Fig. 1 is a diagrammatic view showing one form of apparatus embodying my invention, and Fig. 2 10 is a diagrammatic view showing a modification of the apparatus shown in Fig. 1 and also embodying my invention.

Similar reference characters refer to similar parts in each of the views.

Referring first to Fig. 1, the reference characters 1 and 1^a designate the track rails of a railway over which traffic moves in both directions. These rails are divided by insulated joints 2 to form two track sections A—B and B—C. A highway H intersects the railway track at or near the point B.

Track section A—B is provided with a track circuit comprising a source of current 3, 25 and one magnet 4^a of an interlocking relay R. The other track section B—C is provided with a similar track circuit including the other magnet 4^b of the interlocking relay R. Relay R may be of any suitable type, such, 30 for example, as the relay shown in United States Letters Patent No. 799,452, granted to W. W. Coleman on September 12, 1905. Relay R controls a highway crossing signal S, which may be of any suitable type, but 35 which, as here shown, is a bell. This bell is provided with a circuit which includes a battery 7, and two back contacts 5^a and 5^b, in multiple, of relay R, whereby the bell rings when a train is in either section A—B or 40 B—C approaching the highway H, but ceases to ring while the train is receding from the highway. The control of highway crossing 45 bells and other crossing signals by interlocking relays is well understood and need not be explained in further detail herein.

The magnet 4^a of relay R is provided with a shunt path which includes a back contact 6^a of the armature associated with magnet 4^a; and, similarly, magnet 4^b is provided with a 50 shunt path which includes a back contact 6^a of

the armature associated with magnet 4^a. Each back contact 6^a and 6^b is closed when and only when the associated armature is in the fully released position as taught in the patent identified above.

Assuming that a train moving toward the right enters section A—B, the shunt across the rails of this section, due to the wheels and axles of the train, will deenergize magnet 4^a, so that contacts 5^a and 6^a will close. The closing of contact 5^a causes bell S to ring. The closing of contact 6^a will complete the shunt path around magnet 4^b, so that the armature of this magnet will release, but will of course, not open far enough to close back contacts 5^b and 6^b. When the train enters section B—C, it will have no effect on the armature associated with magnet 4^b, because this armature is already released. When the rear end of the train leaves section A—B, magnet 4^a 55 will become energized to open contacts 5^a and 6^a, and the opening of contact 5^a will cause the bell to stop ringing. The operation during 60 passage of a train moving toward the left will be apparent without explanation.

The auxiliary shunt path for each magnet insures that when a light engine passes rapidly from either track section into the other, the second magnet of the interlocking relay will be de-energized before the first 65 magnet becomes energized, and this insures that the interlocking parts of the relay will 70 function properly.

Referring now to Fig. 2, magnet 4^b of the interlocking relay R is connected with the 75 track rails of section B—C, as in Fig. 1, but magnet 4^a is controlled by a track relay R^x, which is included in the track circuit for section A—B. This arrangement is particularly well adapted for use when magnet 4^a 80 of the interlocking relay is to be controlled by devices other than the track circuit for section A—B. The circuit for magnet 4^a is from a suitable source of current, not shown 85 in the drawing, through apparatus which is likewise not shown in the drawing, then through wire 11, contact 9 of relay R^x, wire 12, front contact 8 associated with magnet 4^b, wire 13, windings of magnet 4^a, wire 14, contact 10 of relay R^x, and wire 11^a to the other 90 95 100

terminal of the source of current. It will be noted that this circuit includes a front contact of the armature associated with magnet 4^b, so that when magnet 4^b becomes de-energized due to a train moving toward the left entering section B—C, magnet 4^a will also be de-energized. Magnet 4^b is provided with a shunt path which includes back contact 6^a of the armature associated with magnet 4^b, this part of the apparatus being exactly the same as in Fig. 1. The operation of the apparatus shown in Fig. 2 is the same as that of the apparatus shown in Fig. 1, except that when a train is moving towards the right, bell S will start to ring as soon as the circuit for magnet 4^a is opened by the device or devices to the left of section A—B which control this circuit.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. Apparatus for protecting an intersection of a railway and a highway, comprising an interlocking relay controlled by trains, and means for controlling each magnet of said relay by the armature associated with the other magnet.
2. Apparatus for protecting an intersection of a railway and a highway, comprising an interlocking relay controlled by trains, and an auxiliary circuit for each magnet of said relay including a contact of the armature associated with the other magnet.
3. Apparatus for protecting an intersection of a railway and a highway, comprising an interlocking relay controlled by trains, and auxiliary means for controlling one magnet of said relay by the armature of the other magnet.
4. Apparatus for protecting an intersection of a railway and a highway, comprising an interlocking relay controlled by trains, and a shunt path for one magnet of said relay including a back contact of the armature associated with the other magnet.
5. Apparatus for protecting an intersection of a railway and a highway, comprising an interlocking relay controlled by trains, and a shunt path for each magnet of said relay including a back contact of the armature associated with the other magnet.
6. Apparatus for protecting an intersection of a railway and a highway, comprising an interlocking relay, the circuit for one magnet of said relay including a front contact of the armature associated with the other magnet, and a shunt path for the second magnet including a back contact of the armature associated with the first magnet.

7. In combination, two adjacent sections of railway track, an interlocking relay, a track circuit for one section including one magnet of said relay, a track circuit for the other section including the other magnet of said relay, and means for controlling each magnet of said relay by the armature associated with the other magnet. 70

8. In combination, two adjacent sections of railway track, an interlocking relay, a track circuit for one section including one magnet of said relay, a track circuit for the other section including the other magnet of said relay, and a shunt path for each magnet of said relay including a back contact of the armature associated with the other magnet. 75

9. In combination, two adjacent sections of railway track, an interlocking relay, a second relay, a track circuit for one section including the first magnet of said interlocking relay, a track circuit for the other section including the magnet of said second relay, a circuit for the second magnet of said interlocking relay controlled by a front contact of said second relay and by a front contact of the armature associated with the first magnet of the interlocking relay, and a shunt path for the first magnet of said interlocking relay including a back contact of the armature associated with the second magnet. 80

In testimony whereof I affix my signature. 85
